MUSICAL INSTRUMENT HOLDER

Filed April 25, 1927

UNITED STATES PATENT OFFICE

GERALD J. HASTEROK AND HENRY TENNES, OF CHICAGO, ILLINOIS

MUSICAL-INSTRUMENT HOLDER

Application filed April 25, 1927. Serial No. 186,199.

Our invention pertains to musical instrument holders and more particularly to a holder especially adapted for banjos, guitars, and the like.

At present there is considerable demand on the market for a holder capable of receiving and maintaining an instrument such as the banjo in a vertical position. The reason for this is that the instrument is more readily accessible to the musician when it is in a vertical position than in any other position; also, when it is in a vertical position it occupies less space and is less apt to be damaged.

We propose to provide a highly simple holder for a banjo or the like adapted to receive and hold the instrument in a vertical position and capable of resisting any force tending to tip the instrument.

In accordance with the features of our invention we provide a metallic frame covered with upholstery or the like supported by a plurality of outwardly slanting legs. The frame is preferably rectangular in shape and is adapted to receive the lower portion of the body of the instrument, such for example as the resonator of the banjo.

In the preferred form of our invention which is adapted to receive a banjo we provide the frame with offset portions capable of bearing against the rim of the banjo.

Other objects and advantages of our invention will more fully appear from the detailed description taken in connection with the accompanying drawing which illustrates several embodiments thereof and in which

Figure 1 is an elevation of the preferred form of our invention showing it supporting a banjo;

Figure 2 is a plan view of the structure shown in Figure 1;

Figure 3 is an enlarged plan view of our novel frame showing a part of the upholstery broken away to illustrate the metallic framework;

Figure 4 is an enlarged detail sectional view taken on substantially the line IV—IV of Figure 3, looking in a direction indicated by the arrows and showing the manner in which the leg is connected to the frame;

Figure 5 is an elevation of another form of

our invention showing it supporting a guitar; and

Figure 6 is a plan view of the holder shown in Figure 5.

In the drawings:

The reference character 10 denotes generally a holder embodying the features of our invention and particularly adapted to support a banjo in a vertical position. In Figures 1 and 2 we have shown a banjo 11 and the manner in which it is supported by the holder 10. The banjo comprises essentially a neck 12, a resonator 13, and a rim 14.

The holder 10 comprises a rectangular frame 15 preferably made of metal rod. This frame is adapted to embrace the lower portions of the resonator 13 and the rim 14. The frame 15 is provided with rectangular offset portions 16, each of which comprises a bent rod 17 suitably secured to a corner of the metallic frame 15. The frame 15 and the portions 16 are covered by a suitable plush upholstery 18. If it is so desired, a covering of rubber may be used in place of the upholstery 18. The two offset portions 16 extend inwardly from the frame rod 15 and are disposed within the dimensions of the frame. These portions are directly opposite each other and are adapted to engage lower portions of the periphery of the rim 14.

The frame 15 is supported by four outwardly slanting legs 20 disposed at the corners of the frame. Each leg comprises a metal rod 21 having its upper end 22 threaded. The lower end of the rod may be provided with a knurled portion 23 by means of which the rod or leg may be turned. The end 22 of each leg is threaded into a sleeve 24 which is threaded into an opening 25 in the tubular rod frame 15. The rod 21 is preferably nickel plated in order to enhance its appearance. Furthermore, it will be evident that the holder 10 may be readily dismantled by unthreading the legs 20 from the frame 15 thus augmenting the portable characteristics of our device.

In use, the holder 10 supports the banjo in a substantially vertical position. In placing the instrument in the holder the instrument is simply dropped downwardly onto

the frame 15. The resonator 13 of the banjo upon falling within the dimensions of the frame immediately aligns itself with the edges of the frame so that the rim is brought to rest on the offset portions 16. Furthermore, due to the slanting legs 20 it is practically impossible to tilt the holder 10 irrespective of the position to which the banjo may be tipped. Obviously this is very desirable since the instrument may be very badly damaged should it fall to the ground. Moreover, our holder occupies relatively little space and may be placed close to the musician's position where the instrument contained in it is readily accessible to the musician. When he is through playing the instrument all he has to do is simply place it on the frame of the holder and it will properly align itself with the holder.

From the foregoing it will also be apparent that our device may be very economically manufactured from metallic tubing. As a whole it presents a pleasant appearance to the eye. Our device is not only useful to musicians but may be used in musical shops as a display stand for the banjo or other instrument.

In Figures 5 and 6 we have shown a modified form of holder 10' which is substantially like that shown in Figure 3, with the exception that it does not contain the offset portions 16. The holder is particularly designed to receive the lower portion of the body 14' of a guitar 11'. The holder comprises a frame 15' and four slanting legs 20' connected thereto, as shown in Figure 4. The periphery of the guitar body 14' abuts against the ends of the frame 15' and the lower portion of the body 14' extends a slight distance below the plane of the frame 15'.

We desire it understood that although we have illustrated and described in detail the preferred forms of our invention, the invention is not to be thus limited, but only in so far as defined by the scope and spirit of the appended claim.

We claim as our invention:

A musical instrument holder for banjos and the like, comprising an elongated horizontal frame of straight side members, the said frame being shaped to receive a portion of the body of a banjo and the like to solely support it in a substantially vertical position, and legs connected to the frame to support it above the floor.

In testimony whereof we have hereunto subscribed our names at Chicago, Cook County, Illinois.

GERALD J. HASTEROK.
HENRY TENNES.
